UNITED STATES PATENT OFFICE.

PETER THOMSEN, OF CASSEL-WILHELMSHOHE, GERMANY, ASSIGNOR, BY MESNE ASSIGNMENTS, TO THE SUPERHEATER COMPANY, OF NEW YORK, N. Y., A CORPORATION OF DELAWARE.

FEED-WATER HEATER FOR LOCOMOTIVES.

Application filed March 30, 1921, Serial No. 457,142, and in Germany November 25, 1916.

The invention relates to feed-water heaters for locomotive boilers, and has for its object to improve the construction of such heaters in order to obtain the maximum degree of heating of the feed-water.

With this object in view, the invention consists in the details hereinafter described.

In the accompanying drawings, which illustrate one form of the invention,

10 Figure 1 shows a vertical longitudinal section through the fire-box of a locomotive,

Figure 2 being an end view, and

Figure 3 a plan partly in section.

According to the form of the invention

15 shown, the feed-water heater tubes *a*, in staggered relation, are supported in vertical longitudinal walls of the box-like pockets or compartments, *h*, of the smoke-box, *e*,

19 bends or caps, *i*, in these compartments connecting the tubes in series. These caps, *i*, are

23 accessible from the outside through openings in the smoke-box wall provided with covers, so that on removing the caps, the

27 inside surfaces of the tubes can be conveniently cleaned from outside the smoke-

box. The outside surfaces of the tubes are also readily accessible and can thus be efficiently cleaned when desired. The feed-water

31 passes into the heater at *k*, and is with- drawn at *l*, so that its direction of flow is

35 opposite to that of the hot gases from the smoke tubes; in addition the heater is placed in the smoke-box at such a height that all

39 boiler tubes *b*, including even the uppermost, as well as the superheater elements, *g*, and

43 their connections to the steam headers, *g*¹, are accessible from the front.

Below the feed water heater a transverse partition is located in the smoke-box *e*, said

47 partition being formed by two members or plates *u*¹, *u*², hinged about vertical axes so

51 that when swung forwardly they will be close to each other and afford a wide open-

55 ing through which access may be had to the smoke tubes *b*, the superheater tubes *g*,

59 the headers *g*¹ and the parts associated therewith. The two members of plates *u*¹, *u*², are

63 provided with cut-out portions at the top to receive individual plates or dampers *u*³ which normally hang down in a vertical position but may be swung upwardly and rear-

67 wardly about a horizontal axis located at their upper edges as indicated in Fig. 1

71 where such plates or dampers *u*³ are shown

as connected with a shaft *o* carrying a hand lever. The purpose of these dampers *u*³ is to attain for a larger or smaller portion of the heating gases, when desired, a direct path to the stack *d*, that is to say, by-passing the feed water heater so that, when starting up the boiler and for temporarily increased effort of the engine, the draft may be increased as required. The transverse partition formed by the members *u*¹, *u*², *u*³, subdivides the smoke-box *e* into two compartments *e*¹ and *e*² of which the forward one *e*¹ contains the blast pipe *m* while the rear compartment receives the cinders and like matter. Thus there is provided for this matter a separate space from which it cannot be carried away by the action of the blast pipe. This compartment *e*² furthermore acts as a throttling device for the intermittent or blow-like action of the blast pipe, thereby insuring a uniform carrying away of the furnace gases by suction from the fire box through the heating tubes *b* and therefore a steady, uniform, combustion of the fuel, and thus a smaller consumption of coal.

Having described my invention, I claim:

1. A locomotive boiler plant comprising a boiler, smoke tubes extending through said boiler, a smoke-box into which said smoke tubes discharge, said smoke-box extending upwardly above the level of the uppermost smoke tubes, a feed water heater located in said smoke-box above the level of the uppermost smoke tubes, an upright partition subdividing the smoke-box portion below the feed water heater into two compartments one communicating directly with the smoke tubes and the other with the outlet of the smoke box and a blast pipe located in that compartment which is distant from the smoke tubes.

2. A locomotive boiler plant comprising a boiler, smoke tubes extending through said boiler, a smoke-box into which said smoke tubes discharge, said smoke-box extending upwardly above the level of the uppermost smoke tubes, a feed water heater located in said smoke-box above the level of the uppermost smoke tubes, a transverse partition subdividing the smoke-box portion below the feed water heater into two compartments, said partition being composed of hinged plates adapted to be opened, and a blast pipe

located in the compartment distant from the smoke tubes.

3. A locomotive boiler plant comprising a boiler, smoke tubes extending through said boiler, a smoke-box into which said smoke tubes discharge, said smoke-box extending upwardly above the level of the uppermost smoke tubes, a feed water heater located in said smoke-box above the level of the uppermost smoke tubes, a transverse partition subdividing the smoke-box portion below the

feed water heater into two compartments, said partition comprising hinged plates mounted to swing about upright axes and damper means located at the upper portion 15 of said partition and swinging about a horizontal axis, and a blast pipe located in the smoke-box compartment distant from the smoke tubes.

In testimony whereof I have hereunto set 20 my hand.

PETER THOMSEN.
